Primary Examiner — Philip S Hyder*Assistant Examiner* — Keith Frank(74) *Attorney, Agent, or Firm* — Clement Cheng(57) **CLAIM**

The ornamental design for a combination trampoline and swing, as shown and described.

DESCRIPTION

FIG. 1 is a perspective view of the pen, showing my new design.

FIG. 2 is a right side elevational view of FIG. 1.

FIG. 3 is a front elevational view of FIG. 1.

FIG. 4 is a left side elevational view of FIG. 1.

FIG. 5 is a rear elevational view of FIG. 1.

FIG. 6 is a bottom plan view of FIG. 1; and,

FIG. 7 is a top plan view of FIG. 1.

The broken lines depict portions of the combined trampoline and swing in which the design is embodied that are not considered part of the claimed design.
